J. A. H. BARKEIJ

INTERNAL COMBUSTION ENGINE

Filed Jan. 15. 1924

Patented June 9, 1925.

UNITED STATES PATENT OFFICE.

JEAN A. H. BARKEIJ, OF LOS ANGELES, CALIFORNIA.

INTERNAL-COMBUSTION ENGINE.

Application filed January 15, 1924. Serial No. 686,320.

To all whom it may concern:

Be it known that I, JEAN A. H. BARKEIJ, a subject of Holland, residing at Los Angeles, in the county of Los Angeles and State of California, have invented a new and useful Internal-Combustion Engine, of which a specification is set forth below.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to internal combustion engines of the four cycle type. Among its principal objects are, to accomplish the introduction of full charges of the explosive mixture when the engine is running at very high speeds; second, to balance in a large measure the inertia forces exerted by the reciprocating masses so as to effectively reduce vibration and permit of high operating speeds; and, third, to secure the above results in a relatively simple construction adapted for delivering a large amount of power in proportion to its dimensions and weight.

My objects are attained in the manner illustrated in the accompanying drawing, in which—

Figure 1 is a central cross section of a complete engine of my improved construction, in elevation;

Figure 2 is an elevational cross section of the upper portion of one of the cylinders of this engine, taken on the line 2—2 of Fig. 1; and

Figure 3 is a cross section of a portion of the engine in plan, taken on the line 3—3 of Figs. 1 and 2.

Similar reference numerals refer to similar parts throughout the several views.

The first of my stated objects is secured by pre-compressing the explosive mixture so that it is admitted to the cylinders under a pressure sufficient to insure that a full charge will be taken in at any operating speed of which the engine is capable. The second object is accomplished by connecting the compression means to cranks diamet-

rically opposed to the main power cranks, so that the respective reciprocating masses always move in opposite directions. By properly proportioning these masses with respect to their travel it is possible to balance their inertia effects quite closely.

The embodiment of my invention selected for illustrative purposes comprises a typical arrangement having two power cylinders 4 and 5. Two cylinders, or multiples of two arranged as co-operating pairs, are always required. Within the power cylinders are pistons 6 of ordinary form, operatively connected to crank shaft 7 by connecting rods 8. It is to be noted that the cranks to which these rods are connected are in the same angular position relative to the crank shaft instead of being opposed according to the customary practice in two cylinder arrangements.

Power pistons 6, instead of being opposed by fixed cylinder heads, re-act against opposed pistons 9 adapted to reciprocate in the upper portion of their respective cylinders. These reaction pistons are enlarged at the top and in effect constitute a part of the large compression pistons 10, adapted to reciprocate in the large compression cylinders 11, which are co-axial with the power cylinders below them. Cylinder heads 12 are provided with central cupped portions 13 adapted to enter the trunks of pistons 9 and thus reduce the compression space to the desired amount. They do not, however, fit the trunks very closely so that an annular space 14 always establishes communication between the interiors of the trunks and cylinders 11.

Compression pistons 10 in each case are operatively connected to the crank shaft of the engine by means of a diametrically arranged pair of connecting rods 15 pivoted to the skirts of these pistons as at 16. The cranks to which these connecting rods are attached are all in the same angular position relative to the crank shaft, and diametrically opposite to the main power cranks to which connecting rods 8 are attached. The throw of the compression cranks is smaller than the throw of the power cranks and as nearly as possible in inverse proportion to the square root of the masses of their attached reciprocating parts. The vibration producing tendencies of the reciprocating masses is largely counterbalanced in this

manner, and much higher engine speeds than would ordinarily be permissible are thus obtainable.

The combustion and expansion of the explosive mixture takes place in the spaces 17 between pistons 6 and 9, and each of these mutually reacting pistons delivers power to the crank shaft of the engine proportionate to their travel. The compressed mixture is admitted into spaces 17 at the proper times through automatic valves 18 and 19 in pistons 9 in a manner that will be explained presently. The mixture is fired by spark plugs 20, and the burned gases are exhausted through mechanically operated valves 21 and ports 22. Intake of explosive mixture into the compression cylinders is accomplished through ports 23 which are opened and closed by the movement of the compression pistons 10. A port 24 establishes communication between the two compression cylinders.

My engine operates in the following manner: Upon the downstroke of compression pistons 10 a vacuum is created in their cylinders and explosive mixture is drawn in through ports 23 as soon as these are uncovered by the pistons. The operating parts are then in the positions shown in the drawings. The succeeding upward stroke of pistons 10 first closes ports 23 and then compresses the explosive mixture above them. During this same period power pistons 6 have moved downward. This movement has created a partial vacuum in space 17 in one case, say in cylinder 4, and this vacuum, aided by the pressure in the two intercommunicating compression cylinders, causes valve 18 to open and admit the compressed mixture into space 17 of the left hand power cylinder. In the case of the other power cylinder 5, the downstroke of the power piston has resulted from the explosion and expansion of the combustible mixture therein and, throughout the stroke, there has been ample pressure in its space 17 to prevent automatic valve 19 from opening.

The next half revolution of the crank shaft is accompanied by a downward movement of the compression pistons and an upward movement of the power pistons. At the ends of these strokes fresh mixture is drawn into the compression cylinders, and the mixture previously introduced in space 17 of the left hand power cylinder has been highly compressed and is ready to be fired.

During the following half revolution of the crank shaft the gas in space 17 of the left hand power cylinder is exploded and expanded and power is delivered to the crank shaft of the engine by the pressure exerted on opposed pistons 6 and 9 of the left hand cylinder. New mixture is also compressed at this time above pistons 10. The next half revolution of the crank shaft is accompanied

by the exhaust of the burned gases in cylinder 4 and taking in a fresh supply of new mixture in the compression cylinders.

The double revolution of the crank shaft, with the corresponding functions of its co-operating parts just described, completes a cycle of operations in cylinder 4, and the performance is then repeated indefinitely. Obviously the same series of operations takes place in the right hand cylinder of the engine, but the cycles of the right hand and left hand cylinders are displaced 360 degrees with respect to each other. One power cylinder is thus engaged in compression as the other exhausts, and fires as the other completes its exhaust stroke.

It will be noted that the power cylinders 4 and 5 operate on a four stroke cycle and that the compression cylinders above them operate on a two stroke cycle. Both the compression cylinders deliver compressed gas to one power cylinder at a time, alternately, by means of the intercommunicating port 24.

I desire to call attention to the fact that the arrangement of parts as herein shown and described permits of having a water jacket 25 completely surrounding the power cylinders throughout the whole of their operative length. These cylinders may be cast integral with casing 26 of the engine and be supported therefrom by means of webs 27.

It is also to be noted that, although power is consumed in pre-compressing the explosive mixture in my engine, there may be an excess of power for this purpose supplied during half of each revolution of the crank shaft beneath one of the two compression pistons. For this reason the net result of the operation of the compression pistons may be to deliver more power to the crank shaft than they take therefrom.

Having thus fully described my invention, I claim:

1. An internal combustion engine comprising; an adjacent pair of cylinders with power pistons therein, and directly intercommunicating counterbores; a pair of differential pistons opposed the power pistons adapted for compressing explosive mixture in said counterbores; and means for introducing and firing the thus compressed explosive mixture between said power and compression pistons; said power pistons being adapted for reciprocating in the same direction, and oppositely the compression pistons.

2. An internal combustion engine comprising; an adjacent pair of cylinders with power pistons therein, and directly intercommunicating counterbores; a pair of differential pistons opposed the power pistons adapted for compressing explosive mixture in said counterbores; and automatic valves in said differential pistons whereby the thus

- compressed explosive mixture may be introduced between them and the power pistons; the pistons of each class being adapted for reciprocating in the same direction oppositely the other class.
5. An internal combustion engine comprising; a pair of cylinders with power pistons adapted for four-cycle operation therein, and inter-communicating counterbores; a pair of differential pistons opposed the power pistons adapted for two-cycle compression of explosive mixture in said counterbores; and automatic valves in said differential pistons whereby the thus compressed explosive mixture may be introduced between them and the power pistons; the pistons of each class being adapted for reciprocating in the same direction oppositely the other class, and all of said pistons being operatively connected to a common crank shaft with their relative throws substantially in inverse proportion to the square roots of their respective reciprocating masses.
6. An internal combustion engine comprising; a pair of cylinders with power pistons adapted for four-cycle operation therein, and inter-communicating counterbores; a pair of differential pistons opposed the power pistons adapted for two-cycle compression of explosive mixture in said counterbores; and automatic valves in said differential pistons whereby the thus compressed explosive mixture may be introduced between them and the power pistons; the pistons of each class being adapted for reciprocating in the same direction oppositely the other class.
7. An internal combustion engine comprising; a pair of cylinders with power pistons adapted for four-cycle operation therein, and inter-communicating counterbores; a pair of differential pistons opposed the power pistons adapted for two-cycle compression of explosive mixture in said counterbores; and automatic valves in said differential pistons whereby the thus compressed explosive mixture may be introduced between them and the power pistons; the pistons of each class being adapted for reciprocating in the same direction oppositely the other class, and all of said pistons being operatively connected to a common crank shaft.
8. An internal combustion engine comprising; a compression chamber having piston means therein for two-cycle compression of explosive mixture; a pair of power cylinders with pistons therein, adapted for four-cycle operation; and automatic means for introducing and firing thus compressed explosive mixture in said power cylinders alternately; said compression piston means being adapted for direct actuation by the exploded charges in said power cylinders.

JEAN A. H. BARKEIJ.
